UNITED STATES PATENT OFFICE.

JAMES HARVEY WILDER, OF RANDALL, KANSAS.

TARGET-TRAP.

1,162,118.

Specification of Letters Patent. Patented Nov. 30, 1915.

Application filed April 8, 1915. Serial No. 19,914.

To all whom it may concern:

Be it known that I, JAMES HARVEY WILDER, a citizen of the United States, residing at Randall, in the county of Jewell 5 and State of Kansas, have invented certain new and useful Improvements in Target Traps, of which the following is a specification.

My invention relates to target traps for throwing clay pigeons, and one important 10 feature of the invention resides in the target carrier which may be readily adjusted to throw one target, or adjusted to throw two targets at the same time.

Other features of the invention will hereinafter appear, and in order that said invention may be fully understood, reference 15 will now be made to the accompanying drawings, in which:

Figure 1 is a side elevation, partly in section of my trap. Fig. 2 is a broken plan view, enlarged, of the same. Fig. 3 is a detail plan view, enlarged, of the target carrier. Fig. 4 is an inverted plan view of the 20 target carrier. Fig. 5 is a cross section on line V—V of Fig. 3. Fig. 6 is a view of an abutment constituting part of the invention. Fig. 7 is a detail section on line VII—VII of Fig. 1.

In carrying out my invention, I employ a stationary base 1, rigidly secured upon a base-board A by bolts 2.

3 designates a turn-table rotatably mounted upon the base 1, it being held in position 35 thereon by a central bolt 4 extending down through the base-board A. The rotatable movement of the turn-table 3 upon the base 1, is restricted by stops 5 and lugs 6, which latter extend upwardly from the base 1.

The stops 5 have pin-and-slot connections 7 with the turn-table 3, so that they may be 40 adjusted forward or backward to bring any of their step-shaped abutting surfaces 8 into contact with the respective lugs 6. By adjusting the stops backward toward the bolt 4, the turn-table 3 may move through a greater arc than when said stops are adjusted forward. The stops 5 are independently-adjustable, so that the turn-table may 45 rotate farther to one side than the other from a line drawn midway through the two lugs 6.

9 designates a segmental arm extending upward and forward from the turn-table 3 and provided with a longitudinal slot 10 to receive a bolt 11, whereby the lower end

of a pivotal U-shaped frame 12 is adjustably connected to said arm 9. The upper rear portion of the frame 12 is mounted upon a pivot 13, carried by the upper ends 60 of a pair of inclined legs 14, extending upward from the turn-table 3 to which they are firmly secured.

15 designates a longitudinal handle secured to the front and rear portions of the 65 frame 12 to swing the same in a horizontal plane, which movement is permitted by the turn-table 3 rotating upon its axis 4.

16 designates a shaft journaled in the forward portion of the frame 12 and provided 70 with a fixedly-mounted lever 17, having a pivoted eye 18, to which the forward end of a main spring 19 is attached, the rear end of said main spring being secured to a tensioning screw 20 extending through a lug 75 21 on the adjacent leg 14. A nut 22 threaded upon the screw 20, serves to adjust the same forward or backward to regulate the tension of the spring 19.

23 designates the target carrier which is 80 rigidly secured to the upper end of the shaft 16 and is of sufficient length to accommodate two targets at the same time. Said target carrier 23 embodies a bottom plate 24 with an integral marginal V-shaped back 25, provided at its inner surface with a longitudinal cushion 26 for the adjacent margins of the targets to abut.

27 designates a retaining arm mounted upon a pivot 28 extending through the bottom plate 24. Said retaining arm coacts with the V-shaped back 25 in holding the targets in position upon the carrier. The retaining arm 27 extends rearward of its pivot 28 and divides into terminals 29 and 90 30, the former of which extends through a slot 31 in the bottom plate 24. A spring 32 is attached at its forward end to the terminal 30 and at its rear end to a hook 33 adapted to pass through either of the key-hole slots 34, 100 35, in the rear margin of the bottom plate 24, to regulate the tension of the spring 32.

From its pivotal point 28 the retaining arm 27 extends upward and forward to lightly engage the adjacent margins of the 105 targets (not shown), and it then bends downward and extends beneath the bottom plate 24 in the form of a curved finger 36, which passes through a loop 37, secured to the underside of the plate 24 to prevent vertical 110 vibration of the arm 27.

The bottom plate 24 has a longitudinal slot

38 divided near its rear end by two transverse bars 39, 40, either of which is adapted to support an abutment 41 having a pair of downwardly and rearwardly extending hooks 42 to embrace either of said bars and thus hold the abutment in position thereon. The abutment is further secured upon either of the bars 39, 40 by a retractile spring 43 secured at its forward end to the abutment 41, and provided at its rear end with a hook 44 adapted to engage either the bar 40 or the rear margin of the bottom plate 24, which latter has a notch 45 to prevent lateral slipping of the hook 44. The front side 15 of the abutment 41 has a cushion 46 to prevent injury to the targets when placed against said abutment.

47 designates a catch secured to the underside of the bottom plate 24, opposite the finger 36. Said catch 47 is adapted to engage a trigger 48, which secures the carrier 23 in set position. Said trigger 48 is mounted upon a pivot 49 extending through the top bar of the frame 12, and has a depending arm 50 which is normally drawn backward by a retractile spring 51 secured at its rear end to a link 52 mounted upon the pivot 13.

Backward movement of the arm 50 is 30 limited by a lug 53 thereon and a set-screw 54 threaded through said lug and engaging the underside of a bearing 55, projecting laterally from the upper bar of the frame 12 to support the adjacent end of the pivot 49. 35 By proper adjustment of the set-screw 54 it is obvious that the trigger 48 may be made to enter the recess in the catch 47 to a greater or less depth to release said catch sooner or later as desired.

40 The trigger 48 is disengaged from the catch 47 through the intermediacy of a lug 56, carried by a releasing-bar 57 supported at its front end by a chain 58 and at its rear end by a link 59, which latter depends from 45 a pivot 60 extending through the rear upper end of the frame 12. The chain 58 extends around a cam 61 and is secured at its forward end to links 62 mounted upon the lower portion of the shaft 16. The cam 61 50 and the link 62 are rigidly secured to the shaft 16, to rotate therewith. The forward end of the releasing bar 57 is restrained from lateral movement by an arm 57^a, pivoted to the upper bar of the frame 12 and 55 having a pin-and-slot connection 57^b, with said releasing bar. The link 59 is controlled by a connecting rod 63, pivotally-secured at its rear end to a lever 64 by a bolt 65. The connecting bar 63 and the lever 64 have 60 holes 66 and 67, respectively, any of which are adapted to receive the bolt 65 when the position of the connecting bar 63 is to be adjusted.

As shown on Fig. 3, the abutment 41 is 65 adjusted for one target, but it may be read-

ily adjusted backward for two targets by hooking it over the bar 40 and then placing the hook 44 of the spring 43 in the notch 45 at the rear of the bottom plate 24. To set the trap, the lever 64 is swung forward 70 in the direction of the arrow *a* (Fig. 1). This movement swings the carrier 23 around to the position of Fig. 2, where it is secured by the trigger 48 engaging the catch 47. To spring the trap the lever 64 is 75 drawn backward to push the releasing-bar 57 forward, so that its lug 56 advances the arm 50 and throws the trigger 48 out of engagement with the catch 47. When this occurs the main spring 19 instantly swings 80 the carrier around to the position disclosed by Fig. 1, causing it to forcibly eject the target or targets. The sweep of the target carrier 23 is yieldingly-checked by the spring 19, after the crank arm 17 has swung 85 backwardly into alignment with said spring. Vertical adjustment of the frame 12 is had by loosening the bolt 11 and swinging said frame up or down upon its pivot 13, and horizontal adjustment of said frame is effected by grasping the handle 15 and swinging said frame to one side or the other to rotate the turn-table 3 on its axis 4.

While I have shown the preferred form of my invention, I reserve the right to make 95 such changes in the construction, arrangement, and proportion of parts as properly fall within the spirit and scope of the claims.

Having thus described my invention, what I claim and desire to secure by Letters Patent, is:

1. In a trap of the character described, a base having two lugs extending upwardly therefrom a turn-table mounted on said base, stops adjustably mounted on said turn-table and having step-shaped abutting surfaces to contact the lugs and limit the rotary movement of the turn-table, a frame mounted upon said turn-table, a target holder operably mounted upon said frame, 105 and means for controlling said target holder.

2. In a trap of the character described, a target holder consisting of a bottom plate, means for holding one or two targets on said 110 bottom plate, an abutment adjustably mounted upon said bottom plate to accommodate one or more targets, and resilient means to assist in holding said abutment in any of its adjusted positions.

3. In a trap of the character described, a target holder consisting of a bottom plate having a longitudinal slot, transverse bars dividing said slot, an abutment adapted to engage any of said transverse bars to accommodate one or more targets, and means for holding said targets on the bottom plate.

4. In a trap of the character described, a target holder consisting of a bottom plate having one or more transverse bars, means 130

on said bottom plate for holding one or more targets thereon, an abutment having hooks to engage any of said transverse bars to accommodate one or more targets, and 5 means to assist said hooks in securing the abutment on the transverse bars.

5. In a trap of the character described, a target holder consisting of a bottom plate, means for holding one or more targets on 10 said bottom plate, an abutment adjustably mounted upon said bottom plate to accommodate one or more targets, a spring to assist in holding said abutment in any of its 15 adjusted positions, and a hook on said spring adapted to engage different points on the bottom plate.

6. In a trap of the character described, a

target holder consisting of a bottom plate, a back extending along one of the margins of 20 said bottom plate, a retaining arm pivotally mounted at the opposite side of the bottom plate to coact with said back in holding one or more targets on the bottom plate, the rear end of said retaining arm being bent downward to extend through a slot in the bottom 25 plate to limit the pivotal movement of the retaining arm, and a spring engaging said retaining arm and the bottom plate to yieldingly press the retaining arm toward the target or targets.

In testimony whereof I affix my signature.

JAMES HARVEY WILDER.
